CARTON ERECTING MACHINE

Robert Otto Woelfer, Rahway, N. J., assignor to
 Container Equipment Corporation, Newark,
 N. J., a corporation of New Jersey

Application August 14, 1948, Serial No. 44,257

3 Claims. (Cl. 93—53)

1

This invention relates to improvements in machines for closing and sealing pasteboard cartons of the general type shown e. g. in United States Letters Patent No. 2,390,107 to Kucklin-sky, dated December 4, 1945.

An object of this invention is to provide a carton closing and sealing machine with novel means for automatically feeding initially flatly collapsed cartons from a stack thereof into the receiving end of the machine, and thereupon expanding or squaring the carton bodies, and thus set up the same in open condition ready for reception of articles desired to be inserted thereinto, means being provided for closing and sealing one end of a carton, whereafter, by the further operation of the machine, the remaining end of a filled carton is closed and sealed ready for discharge from the machine.

Another object of the invention is to provide the machine with a filling station zone having means for moving an article into aligned opposition to an open end of an expanded carton, so as to facilitate insertion of the article into said carton; means being further provided for closing at least partially the opposite end of the carton while the latter is moving into and through the filling station zone.

Other objects of the invention, not at this time more particularly enumerated, will be understood from the following detailed description of the same.

An illustrative embodiment of the invention is shown in the accompanying drawings, in which:

Fig. 1 is a plan view of the receiving end portion of a carton closing and sealing machine which is equipped with the novel carton feeding and opening mechanism and with the article positioning means, as well as other improved features according to this invention; Fig. 2 is a longitudinal vertical sectional view, taken on line 2—2 in Fig. 1, but drawn on a somewhat enlarged scale; Fig. 3 is a view similar to that of Fig. 2, but showing a delivered collapsed carton in the act of being expanded or squared by the carton opening mechanism; Fig. 4 is a fragmentary elevational view, in the plane of line 4—4 in Fig. 1, but drawn on an enlarged scale, the same showing the means for controlling movements of a top suction device which forms a part of the carton opening mechanism; Fig. 5 is a view similar to that of Fig. 4, but showing the top suction device in the course of its lift-ing movement.

Fig. 6 is a fragmentary plan view in part sec-

2

tion of portions of the means for closing carton side flaps at the end of a carton opposite to that which is presented in open condition for the reception of an article.

Fig. 7 is a fragmentary vertical longitudinal section, taken on line 7—7 in Fig. 1 showing the means for moving an article into aligned opposition to the open end of a carton into which it is desired to introduce said article; and Fig. 8 is a transverse vertical section, taken on line 8—8 in Fig. 1.

Similar characters of reference are employed in the above described views, to indicate corresponding parts.

15 The accompanying drawings show the receiving end portion of a carton closing and sealing machine of the general type disclosed in the hereinabove referred to United States Letters Patent No. 2,390,107, said machine being provided with a pair of laterally spaced, longitudinally extending and parallel channeled track bars 10, through which run the respective upper, forwardly moving, operative courses of a continuously running carton propelling conveyer chains 11. Said conveyer chains are supported and driven by sprockets, including idler sprockets 12 over which run the lower return courses of said chains. The shafts 13 of the sprockets 12 are journaled in bearing hangers 14. Said bearing hangers 14 depend from longitudinal bars 15 which form parts of the machine framework. From the sprockets 12, the conveyer chains 11 are led over supporting guide members 10' to and for entrance into the channeled track bars 10. Mounted upon the conveyer chains 11, at suitably spaced longitudinal intervals, therealong, are carton propelling members 16, which engage the rear sides of cartons, as supported upon and in bridging relation across the track bars 10, whereby to move the cartons forwardly through the machine.

Extending outwardly from the entrance ends of the track bars 10, respectively in substantial longitudinal alignment with the respective sides of the latter, are fixed outer supporting rails 17 and fixed inner supporting rails 18, the upper edges of which lie flush with the plane of the tops of said track bars 10. These rails 17 and 18 provide in part the bottom of a magazine for holding a stack of initially flatly collapsed cartons C.

Affixed to each outer supporting rail 17, to project laterally outward therefrom, are a pair of parallelly spaced carrier rods 19, the outer ends of which are bridged by a stationary cross-

piece 20. Slidably mounted on each pair of carrier rods 19 is a cross-head 21. Mounted in each cross-piece 29, to swivel therein, is an adjusting screw 22, the shank of which is threaded through the corresponding cross-head 21, so that turning of the adjusting screw in selected direction operates to move said cross-head inwardly or outwardly upon the carrier rods 19 for purposes hereinafter explained. Fixed to each cross-head 21 is an inner upstanding angle bar 23; said angle bars 23 define the inner corners of the magazine which is adapted to hold a stack of initially flatly collapsed cartons. Suitably affixed to each inner angle bar 23, to extend longitudinally and horizontally outward therefrom, is a slotted side arm 24, to the free end portion of which is adjustably secured, by a clamp nut means 25, an outer upstanding angle bar 26; said angle bars 26 define the outer corners of the magazine which is adapted to hold the stack of initially flatly collapsed cartons.

Carton delivery means is provided for withdrawing the bottommost collapsed carton C from a stack of cartons held in the previously described magazine, and thereupon advancing the same for deposit upon and across the receiving end portions of the channeled track bars 10 in position to be engaged by conveyer chain carried carton propelling members 16, so as to be moved by the latter through and subject to the operation of carton expanding or squaring mechanism, and thence past the carton filling station or zone and through carton end flap closing and sealing mechanisms with which the machine is provided.

The carton delivery means comprises a pair of delivery chains 27 which are respectively disposed to run contiguous to the inner sides of the respective channeled track bars 10 and the inner supporting rails 18 which extend from the latter. Said delivery chains 27 are continuously driven by inner drive sprockets 28, the shafts 29 of which are journaled in the hanger bearings 14. Said delivery chains run over outer idler sprockets 30, the shafts 31 of which are journaled in outer bearing portions 32 with which the outer ends of said inner supporting rails 18 are provided. The forwardly moving courses of the delivery chains 27 pass beneath the bottom of the magazine, and said courses are supported against sag by supporting bars 33, which are respectively fixed to the inner faces of the inner supporting rails 18 and of the receiving end portions of the channeled guide bars 10. Mounted on the delivery chains 27, at spaced longitudinal intervals therealong, which intervals correspond to the spacing of the carton propelling members 16 on the conveyer chains 11, are push fingers 34. Said push fingers 34 are so shaped and are adapted to so project from the top of the forwardly moving courses of the delivery chains 27, as to pass through the bottom of the previously described magazine and, in so passing, to engage the rearward edge of the bottommost carton C of the stack of cartons held in said magazine, and thus to propel said bottommost carton forwardly out of said magazine, and thereupon advance it so as to deposit the same upon and across the channeled track bars 10 in position to be thereafter operatively engaged by carton propelling members 16 of forwardly moving courses of the conveyer chains 11 which ride in said channeled track bars 10 (see Fig. 2). The lower ends of the inner angle bars 23

of the magazine structure are spaced relative to the top planes of the supporting rails 17 and 18 so as to provide a carton discharge passage or opening 35 at the inner side of said magazine structure. The said passage or opening 35 is of height adapted to permit outward movement of a bottommost carton C, while retaining all cartons above the latter against outward movement or displacement.

The delivery chains 27 are driven, from shafts 13 by chain and sprocket transmission 28 at a speed which synchronizes with the speed of the conveyer chains 11, so that the movements of the push fingers 34 are properly coordinated with the movements of the carton propelling members 16, so that a delivered carton is assured of properly timed deposit upon the receiving end portions of the track bars 10 in advance of the approach of carton propelling members by which such carton is to be moved through the machine.

Secured to outer sides of the respective track bars 10, so as to be laterally offset therefrom at locations beyond but adjacent to the discharge side of the magazine structure, are bracket members 36 having upstanding slotted supporting posts 37. Said posts 37 are disposed in laterally opposed and aligned relation. Supported by said respective posts 37, on inwardly extending arms 38 adapted to be affixed to the latter, are inverted U-shaped hanger brackets 39, each having a dependent outer hanger plate 40 and a dependent inner hanger plate 41. Said hanger brackets 39 respectively overhang the respective track bars 10. The outer hanger plates 40 support forwardly extending keeper rails 42, which preferably lie in the vertical planes of the outer side portions of the respective track bars 10. The inner hanger plates 41 support forwardly projecting fulcrum bars 43. These fulcrum bars 43 are slidably supported by and between guide gibs 44 with which said inner hanger plates 41 are provided. Said fulcrum bars 43 are longitudinally slotted for engagement with clamp stud and nut means 45 by which the same may be locked to the inner hanger plates 41 in desired longitudinally adjusted positions. Said hanger brackets may be vertically adjusted upon the supporting posts 37, whereby to space the keeper rails 42 and fulcrum bars 43 relative to the track bars 10, according to the height of a given expanded or opened carton desired to be operated upon by the machine.

Pivottally connected with the forward free end portions of the respective fulcrum bars 43, so as to freely swing in vertical planes, are carton detent lever arms 46 which form an important part of the carton expanding or opening mechanism according to this invention. Said detent lever arms 46 terminate at their free ends in carton engageable detent means adapted to be engaged by the leading edge of a collapsed carton C as advanced by the carton propelling members 16 of the conveyer chains 11. In a preferred form of said carton engageable detent means, the detent lever arms are provided at their free ends with downwardly offset bearing ears 47, and rotatably mounted on journal studs 48, carried by said bearing ears, are detent rollers 49. The peripheries of each detent roller, at its inner or rearward side, angularly intersects the under edge of the detent lever arm 46 with which it is associated, whereby to form a receiving notch, at the juncture of such intersection, in which the leading edge of a collapsed carton

C may engage; which leading edge is formed by the juncture of a leading side panel and a top face panel of the collapsed carton. Preferably the detent rollers are provided with anti-friction bearings (not shown), whereby the same may rotate with a minimum of resistance about the journal studs 48 by which they are supported.

Extending forwardly from the magazine structure, at each side thereof, is an aligning strip or stop 50. A collapsed carton C, as it is issued from the magazine structure, is caused to pass between said strips or stops, so that the latter respectively abut opposite ends of the collapsed carton, thus retaining the same against endwise shifting displacement, both as it is moved to a position to be operated upon by the carton expanding or opening mechanism and while it is undergoing expanding or opening manipulation.

Said supporting posts 37 are each provided with a rearwardly projecting arm 51, to the free end portion of which is pivotally connected a vertically swingable link 52. Pivotally attached to the free end portions of the respective links 52 are weighty hold-down shoes 53, which are superposed upon and aligned with underlying portions of the outer supporting rails 17 and the track bars 10. As a collapsed carton C issues from the magazine structure, end portions of said collapsed carton pass beneath said shoes 53, so that the latter bear, under gravity, upon said end portions, and thus hold the collapsed carton flatly down upon the supporting guide rails 17 and track bars 10 until it is brought into position to be operated upon by the carton expanding or opening mechanism.

The hereinbefore described detent lever arms 46 are subject to down swinging movements under gravity, and the same are provided with laterally projecting stop lugs 54, which are adapted to abut the track bars 10, whereby to limit the down swinging movements of said detent lever arms 46 and thus establish normal initial positions thereof. When said detent lever arms 46 are thus arrested in down swung normal initial positions, the detent rollers 49 are disposed to lie in the path of forward movement of a collapsed carton C, as the latter is engaged and advanced by the carton propelling members 16 of the conveyer chains 11. Under these circumstances, the leading edge of said collapsed carton is carried into the receiving notches formed where the lower edges of the detent lever arms 46 and peripheries of the rollers 49 intersect as above mentioned (see Fig. 2).

Since the forward movement of the propelling members 16 is continuous, the collapsed carton C, once engaged between said propelling members 16 and the detent rollers 49, is subjected to expanding or opening stresses by reason of the fact that its top face panel t is temporarily detained against that movement by the engaging detent rollers 49, while the bottom face panel b is moved onward by the engaging propelling members 16. As a result of this, the forward side panel f and the rearward side panel r are caused to swing upward about the hinging junctures between the same and the bottom face panel b, while at the same time the top face panel t swings about its hinging junctures with said side panels (see Fig. 3). These movements continue until the side panels stand erect, i. e. perpendicularly to the top and bottom face panels t and b, with said rearward side panel r abutted flatly against the thrusting faces of the propelling members

16, and with the raised top face panel t abutted against the under edges of the keeper rails 42, thereby completing the setting up of the thus manipulated carton in expanded or open condition.

After the carton is thus expanded or opened, continued forward movement thereof, under the impulsion of the propelling members 16, exerts irresistible thrust against the detent rollers 49 which causes the latter to ride upwardly over the leading edge of the raised top face panel t, with accompanying continued upswing of the detent lever arms 46, whereby the open carton is freed from the restraint of these parts as it moves onward under the impulsion of the propelling members 16.

The carton opening mechanism, as thus far described, may alone be employed for the carton opening operation when the cartons to be operated upon are of small size or are of larger sizes made of comparatively stiff pasteboard or cardboard. In many cases, however, the cartons to be manipulated may be of extra large size, or may be made of thin and easily flexed stock, or may possess face panels which are weakened by window openings with or without glazing of transparent cellulosic material or the like. In such cases, it is generally desirable to provide the carton opening mechanism with auxiliary pneumatic devices which are adapted to cooperate with and to function in coordinated relation to the already described carton opening mechanism.

Said auxiliary pneumatic devices comprise a carton bottom face panel suction effected gripper means and a carton top face panel suction effected gripper means; each said means being provided with means for properly timing and controlling its operative engagement with said respective parts.

In a preferred form and arrangement thereof, as shown, the carton bottom face panel gripper mechanism comprises a slideway member 55 which is affixed to and depends from a framework bar 15 beyond but adjacent to the inner ends of the delivery chains 27. Said slideway member 55 is provided on its inner face with a slideway channel 56 by which is guided a vertically reciprocable slide block 57. Affixed to said slide block 57 is a suitably shaped, forwardly extending carrier member 58. Mounted on the lower end portion of said slideway member 55 is a rotatable cam 59 which operatively engages a roller stud 60 on the lower end portion of the slide block 57, whereby to produce suitably timed vertical reciprocatory movements of said slide block and the carrier member 58 supported thereby. The shaft 61 of cam 59 is journaled in the lower end portion of the slideway member 55, and is driven by chain and sprocket transmission 62 from the shaft 13 of one of the sprockets 12 over which a conveyor chain 11 runs. Pivotally supported upon the carrier member 58 is an oscillatable carrier lever 63. The upwardly extending arm of said carrier lever 63 is yieldably held in a rearwardly swung normal initial position, which position is determined by the engagement of a stop lug 64 thereof with a stationary stop post 65 with which the carrier member 58 is provided. The carrier lever is yieldably held in said normal initial position by a pull spring 66 which is connected between its lower arm and a spring anchoring bracket 67 which is affixed to and depends from said carrier member 58.

Attached to the free end portion of the upper

arm of the carrier lever 63, by a holding clip 68, is a flexible air hose 69. The upper end portion of said air hose extends upwardly between the track bars 10, and attached to the upper extremity of said hose is a suction cup 70. The hose 69 extends to an air exhaust pump (not shown), by means of which air may be exhausted from the suction cup 70 so as to permit the latter to exercise suction induced grip upon the bottom face panel *r* of a carton, when the latter is brought into position to be operated upon by the carton opening mechanism.

In the operation of the described carton bottom face panel gripper mechanism, when a collapsed carton reaches a position on the supporting channeled track bars 10 at which it makes initial engagement with the detent lever arms 46 and their detent rollers 49, and is subject to forward impulsion by the carton propelling members 16, the rotating cam 59 is adapted to apply its high part to and with upward sliding effect upon the slide block 57. The upward movement thus imparted to the slide block 57 moves the carrier member 58 and carrier lever 63 upward, whereby to raise the suction cup 70 into suction gripping relation to the underside of the carton bottom face panel *b* (as shown in Fig. 2), so that said panel *b* is held flatly down upon the supporting track bars 10 against upward displacement therefrom, while the top face panel *t* is being raised to expand or open the carton. Since the carton is being advanced along the track bars 10 while its bottom face panel *b* is thus gripped by the suction cup 70, said suction cup will be carried forward therewith. Such forward movement of the gripping suction cup 70 is permitted by the yielding forward swing of the carrier lever 63 against the tension of the pull spring 66 (see Fig. 3). By the time the forward movement of the carton in conjunction with the above described carton expanding or opening effect of the detent lever arms 46 and their detent rollers 49 completes the expanding or opening of the carton, the rotating cam 59 carries its low part into opposition to the slide block 57, so that the latter moves downward. The downward movement of said slide block 57 lowers the carrier member 58 and carrier lever 63, thus downwardly withdrawing the suction cup 70 and breaking the vacuum therein so as to release said cup from the carton bottom face panel *r*, whereafter the carrier lever 63 swings forward and returns to its normal initial stopped position, all whereby the bottom face panel suction gripper means is reset for repetition of its above described operations when a succeeding collapsed carton is presented for expanding or opening manipulation.

A preferred form and arrangement of carton top face panel suction effected gripper means, as shown, comprises a carrier lever 71 which is pivotally supported for oscillation in a vertical plane. To so support said carrier lever 71, one of the previously described supporting posts 37 is provided with a rearwardly offset, upstanding bearing arm 72, to which the rearward end of said carrier lever 71 is pivotally connected at 73. Affixed to the forward free end portion of the carrier lever 71 is an inwardly extending rod or arm 74 of such length that its free end overhangs the channeled track bars 10 so as to lie in a vertical plane intermediate the latter. Attached to the free end of the rod or arm 74, by a holding clip 75, is a flexible air hose 76. A downwardly extending free end portion of said air hose terminates in a suction cup 77, so that the latter is

downwardly directed toward a carton advanced over said channeled track bars 10. The oppositely extending body portion of said air hose 76 is led to an exhaust pump (not shown), by means of which air may be exhausted from the suction cup 77, so as to permit the latter to exercise suction induced grip upon the top face panel *t* of a carton *C*, when said carton is brought into position to be operated upon by the carton opening mechanism. Means is provided for producing timed oscillation of the carrier lever 71, said means comprising an actuating crank arm 78 which is mounted on and revolved by the shaft 13 of one of the sprockets 12 over which a conveyer chain runs. Connected by its lower end to said crank arm 78 is a connecting rod 79, the upper end of which is pivotally coupled at 80 to the carrier lever 71 at a point intermediate the ends of the latter.

In the operation of the above described carton top face panel gripper mechanism, when a collapsed carton reaches a position on the supporting track bars 10 at which it makes initial engagement with the detent lever arms 46 and their detent rollers 49, the revolving crank arm 78 moves through its downswinging phase, whereby to swing downwardly the carrier lever 71, and thus to lower the suction cup 77 into suction gripping relation to the carton top face panel *t* (see Fig. 2). As the carton bottom face panel *b* is advanced along the track bars 10 while the top face panel *t* is detained with rising movement to effect the carton expanding or opening manipulation hereinbefore described, the crank arm 78 is timed to pass into and through its upswinging phase so as to swing upward the carrier lever 71 with accompanying rising movement of the suction cup 77, whereby the latter retains its suction grip upon said top face *t* and thereby assists the rising movement of said panel (see Fig. 3). After the top face panel *t* reaches its fully raised position so as to abut the keeper rails 42, the upswinging movement of the crank arm 78 and carrier lever 71 continues to the limit of its upward movement, thus lifting the suction cup 77 relative to the carton to break the vacuum therein so as to release the grip of the suction cup upon the carton top face panel *t*, as the expanded or opened carton is moved onward along the track bars 10. This completes the cycle of operation of the carton top face panel gripper mechanism and resets the same for repetition of its above described operations, when a succeeding collapsed carton is presented for expanding or opening manipulation.

The carton most commonly employed is of the type which is provided at each end with side flaps *s* and *s'* and top and bottom flaps *x* and *y*.

After a carton *C* has been expanded and thus set up in endwise open condition, its advance over the guide bars 10, under the impulsion of the propelling members 16, causes the same to traverse a filling station zone which is located at one side of the machine. As the carton moves relative to the filling station zone, means is provided, at the side of the machine opposite to that at which said filling station zone is located, which operates to at least close the side flaps *s* and *s'* at the end of the carton remote from the filling station or zone. The means for effecting closing manipulation of these side flaps comprises a stationary folder rail 80 having at its rearwardly directed end an outwardly and rearwardly inclined folding plow 81 by which the leading side flap *s* is engaged as the carton moves to pass behind said

folder rail 80. The engagement of the side flap 3 by said folding plow 81 causes the flap to be swung inwardly across the adjacent open end of the carton, the inswung flap s' thence passing behind the folder rail 80 by which it is retained in said inswung closed relation to the carton end. A rotary folder device is provided for thereafter inswinging the trailing side flap s'. This rotary folder device comprises an oscillatable arm 82, which is adapted to be swung forward and back in horizontal plane, and which is provided at its free end with suitably shaped forwardly directed folder finger means 83. Said folder arm 82 is fixed on the upper end of a suitably journaled perpendicular shaft 84. Means to oscillate said shaft 84, and thus effect suitably timed oscillatory movement of the arm 82 and its folder finger means 83 comprises an actuating lever 85 fixed on the lower end of said shaft. Mounted in the machine, and adapted to be suitably connected with the power transmission of the latter (not shown), so as to be driven thereby, is a rotatable shaft 86 to which is fixed a crank arm 87. Interconnected between said crank arm 87 and the actuating lever 85 of the oscillatable shaft 84 is a connecting rod 88 (see Fig. 6). The crank arm 87 is revolved in such timed relation to the carton advancing speed of the conveyer chains 11 and its carton propelling members 16 as to initiate a forward swing of the oscillatable arm 82 after each carton reaches a position at which the leading side flap s is about to be engaged and infolded by the folding plow 81. As the carton moves past said folding plow 81, so that the leading side flap s is engaged and inswung thereby, the forward swing of the arm 82 carries its folder finger means 83 against the outer face of the trailing side flap s', whereby to inswing this flap at least to the extent that its free end will be engaged by the folding plow 81, and then guided by the latter to pass behind the folder rail 80 and thereby held in fully inswung closed relation to the adjacent open end of the carton. After the trailing side flap s' is thus manipulated and closed, the arm 82 is swung back to normal initial position, ready to repeat its folding operation upon the next succeeding open carton as it is advanced to pass through the filling station zone.

At the filling station zone is located means for moving an article into aligned opposition to an open end of an expanded carton, when the latter is presented for reception of said article. This means comprises a pair of laterally spaced endless conveyer chains 89 which run parallel to the carton conveyer chains 11. Said conveyer chains 89 are supported by sprockets 90 and 91, the sprockets 90, which serve as driving sprockets, being mounted on an extension of a shaft 29 which drives a sprocket 28 by which a carton delivery chain 27 is actuated. As thus driven, said conveyer chains 89 are moved at a speed in synchronism with the speed of said carton delivery chains 27 and that of the main carton conveyer chains 11. Supported by suitable standards 92, above and contiguous to the upper forwardly moving courses of the conveyer chains 89, is a loading table 93. Bridging the conveyer chains 89 are article aligning push-bars 94. These push-bars 94 are spaced along the conveyer chains at the same intervals as that of the push fingers 34 on the carton delivery conveyer chains 27 and as that of the carton propelling members 16 on the main conveyer chains 11. The opposite end portions of said push-bars 94 respectively overhang the opposite side margins of the loading

table 93, and are affixed to the respective conveyer chains 89 by offset brackets 95 with which the exterior sides of said conveyer chains are provided, said brackets 95 having upstanding posts 96, which straddle the loading table, and to which the overhanging ends of the push-bars are rigidly attached. By reason of such offset connection of the push-bars 94 with the conveyer chains 89 by which they are carried, said push-bars, in operation, will be carried over the rearward end of the loading table 93 so as to thereafter be caused to slide forwardly upon the top surface of the loading table, when advanced by the forwardly moving courses of said conveyer chains (see Figs. 7 and 8).

Suitably supported adjacent to the rearward end of the loading table 93 is an article receiving chute 97, the inner end of which is spaced from the rear end of the loading table so as to provide an intermediate clearance passage 98 through which the push-bars may pass onto the top surface of the loading table. Similarly, suitably located and supported adjacent to the forward end of the loading table is an article discharge chute 99, the inner end of which is likewise spaced from the forward end of the table so as to provide an intermediate clearance passage 100 through which the push-bars may pass off from the loading table. Defective articles may be allowed to pass off the loading table onto the discharge chute, from which the same may be removed.

Means is provided for holding the top and bottom flaps x and y, at the open end of a carton C which is opposed to the filling station zone, respectively in upwardly inclined and downwardly inclined positions, and so as to be prevented from offering impedance to movement of an article from the loading table 93 into the carton C.

The means which is operative upon the top flap x comprises a longitudinally disposed, laterally and upwardly inclined top fender plate 101, the same being supported by carrier bracket means 102 adapted to be affixed to and extend from an adjacent keeper rail 42. As thus disposed, said top fender plate 101 lies between the open end of a presented carton C and the inner side of the loading table 93. At its rearward end, said top fender plate 101 is provided with a somewhat downwardly inclined guide tongue 103. As an expanded carton approaches the filling station zone, said guide tongue 103 passes beneath the extending top flap x so as to lift and guide the same onto the upper surface of the top fender plate 101 (see Figs. 1 and 8). When thus supported by the top fender plate, said top flap x is held upwardly inclined and out of the path of an article when the latter is pushed off the loading table and into and through the open end of the presented carton C.

The means which is operative upon the bottom flap y also comprises a longitudinally disposed but laterally and downwardly inclined bottom fender plate 104 which is supported by carrier bracket means 105 adapted to be affixed to and extend from an adjacent channelled track bar 10. Said bottom fender plate 104 also lies between the open end of a presented carton C and the inner side of the loading table 93. At its rearward end, said bottom fender plate 104 is provided with a somewhat upwardly inclined guide tongue 106. As an expanded carton approaches the filling station zone, said guide tongue 106 passes over the extending bottom flap y so as to depress and guide the same to pass beneath the bottom fender plate (see Figs. 1 and 8). When

11

thus depressed by the bottom fender plate, said bottom flap *y* is held downwardly inclined and out of the path of an article when the latter is pushed off the loading table and into and through the open end of the presented carton C.

The filling station zone is designed to be manned by an attendant. Articles which are to be inserted into cartons which are opened and presented during the operation of the machine at the filling station zone, are moved by the attendant or an assistant from the receiving chute 97 onto the rearward end of the loading table 93, so as to lie in the path of movement of an approaching article aligning push-bar 94. An article thus deposited upon the loading table is engaged by a forwardly moving push-bar 94 and advanced over the table surface to the point at which an open carton C is presented for its reception. The position of the article engaging push-bar 94 relative to the carton propelling members 16 by which an open carton is being simultaneously advanced is such that, as said carton moves to article receiving position, said engaging push-bar will be aligned with the rear side panel *r* of the carton, so that, on arrival of the carton in article receiving position, the attendant may push said article by hand through the presented open end of the carton and into the interior thereof. In so doing, the push-bar is utilized by the attendant as a means for guiding the movement of the article into the carton.

It will be understood that the carton closing and sealing machine, in which the above described novel mechanisms are designed to be incorporated, is usually provided, beyond the filling station zone, with devices for completing the closing and sealing of the closure flaps at both ends of the filled carton. Since various types and forms of devices for such purposes are well known and per se form no part of the instant invention, the same have not been shown.

It will also be understood that carton closing and sealing machines adapted to be adjusted to accommodate the functional parts thereof for operation upon various selected sizes of cartons are also known to the art; an example of such type of adjustable machine being disclosed in the hereinbefore mentioned in Patent No. 2,390,107 to Kucklinsky. In such machines, the carton conveyer mechanism and associated flap closing and sealing devices are laterally expandable and contractible to adjust the same to a carton of given length. The keeper rails 42 together with the fulcrum bars 43 which support the carton detent lever arms 46 may be vertically adjusted upon the slotted supporting posts 37 to accommodate the same to a carton of given height. Also magazine angle bars 23 and 24 are relatively movable toward and from each other, whereby to selectively size the magazine for the reception of collapsed cartons of given dimensions.

For the purposes of explaining the instant invention and its mode of operation, it has been desirable to describe in some detail particular constructions shown in the drawings by way of illustration, but it will be obvious that the invention is capable of various embodiments, with suitable changes in the construction and relative arrangement of the parts. It is therefore not desired that the invention be limited by the drawings and the foregoing description except to that extent indicated by the scope of the following claims.

I claim:

1. In a carton closing and sealing machine 75

12

having track means to support cartons moved through the machine and a continuously running main conveyer for propelling the cartons along said track means, means for supplying collapsed cartons to the machine comprising a magazine mounted adjacent to the receiving end of said track means to hold a stack of collapsed cartons, a continuously running carton delivery conveyer traversing the bottom of the magazine and having push fingers to engage and withdraw bottommost cartons from the magazine, the discharge end of said carton delivery conveyer lapsing the receiving end portion of the track means and the associated main conveyer whereby to deliver withdrawn collapsed cartons onto the track means subject to advance along the latter by the main conveyer, at least one pivoted detent lever arm disposed to overhang the track means subject to swinging movement toward and from the latter, said detent lever arm being adapted to engage a delivered collapsed carton at the juncture of its upper face panel and leading side panel so as to detain and lift said upper face panel while advance of the bottom face panel over the track means is effected by the main conveyer, thereby to expand the carton to endwise open condition, a bottom suction gripper means adapted to be moved into engagement with the bottom face panel of the collapsed carton so as to hold the same against displacement from the track means while advanced thereover by the main conveyer, and an oscillatable top suction gripper means adapted to be lowered to engage the upper panel of the collapsed carton and, when thereafter raised, to assist in lifting said upper panel for carton expanding effect, said top suction gripper means comprising a pivoted carrier lever mounted above the receiving portion of the track means for swinging movement toward and from a carton on the track means, a flexible air suction hose affixed to the free end of said carrier lever, said hose having a free end portion dependent from the carrier lever and terminating in a carton engageable suction cup, a rotated crank-arm to produce timed oscillation of the carrier lever, and a connecting rod connecting said carrier lever with the crank-arm.

2. In a carton closing and sealing machine having track means to support cartons moved through the machine and a continuously running main conveyer for propelling the cartons along said track means, means for supplying collapsed cartons to the machine comprising a magazine mounted adjacent to the receiving end of said track means to hold a stack of collapsed cartons, a continuously running carton delivery conveyer traversing the bottom of the magazine and having push fingers to engage and withdraw bottommost cartons from the magazine, the discharge end of said carton delivery conveyer lapsing the receiving end portion of the track means and the associated main conveyer whereby to deliver withdrawn collapsed cartons onto the track means subject to advance along the latter by the main conveyer, at least one pivoted detent lever arm disposed to overhang the track means subject to swinging movement toward and from the latter, said detent lever arm being adapted to engage a delivered collapsed carton at the juncture of its upper face panel and leading side panel so as to detain and lift said upper face panel while advance of the bottom face panel over the track means is effected by the main conveyer, thereby to expand the carton to endwise open condition, a bottom suction gripper

means adapted to be moved into engagement with the bottom face panel of the collapsed carton so as to hold the same against displacement from the track means while advanced thereover by the main conveyer, said bottom suction gripper means comprising a vertically reciprocable carrier member mounted beneath the receiving end portion of the track means, means to produce timed reciprocation of said carrier member toward and from a carton on the track means, a carrier lever pivotally mounted on the carrier member subject to forward and back swinging oscillation, means to yieldably hold said carrier lever in normal initial back swung position, a flexible air suction hose affixed to the upper free end of said carrier lever, and said hose having an upwardly projecting free end portion terminating in a carton engageable suction cup, and an oscillatable top suction gripper means adapted to be lowered to engage the upper panel of the collapsed carton and, when thereafter raised, to assist in lifting said upper panel for carton expanding effect.

3. In a carton closing and sealing machine having track means to support cartons moved through the machine and a continuously running main conveyer for propelling the cartons along said track means, means for supplying collapsed cartons to the machine comprising a magazine mounted adjacent to the receiving end of said track means to hold a stack of collapsed cartons, a continuously running carton delivery conveyer traversing the bottom of the magazine and having push fingers to engage and withdraw bottommost cartons from the magazine, the discharge end of said carton delivery conveyer lapsing the receiving end portion of the track means and the associated main conveyer whereby to deliver withdrawn collapsed cartons onto the track means subject to advance along the latter by the main conveyer, at least one pivoted detent lever arm disposed to overhang the track means subject to swinging movement toward and from the latter, said detent lever arm being adapted to engage a delivered collapsed carton at the juncture of its upper face panel and leading side panel so as to detain and lift said upper face panel while advance of the bottom face panel over the track means is effected by the main conveyer, thereby to expand the carton to endwise open condition, a bottom suction gripper means adapted to be moved into engagement with the bottom face panel of the collapsed carton so as to hold the same against displacement

from the track means while advanced thereover by the main conveyer, said bottom suction gripper means comprising a vertically reciprocable carrier member mounted beneath the receiving end portion of the track means, means to produce timed reciprocation of said carrier member toward and from a carton on the track means, a carrier lever pivotally mounted on the carrier member subject to forward and back swinging oscillation, means to yieldably hold said carrier lever in normal initial back swung position, a flexible air suction hose affixed to the upper free end of said carrier lever, and said hose having an upwardly projecting free end portion terminating in a carton engageable suction cup, an oscillatable top suction gripper means adapted to be lowered to engage the upper panel of the collapsed carton and, when thereafter raised, to assist in lifting said upper panel for carton expanding effect, said top suction gripper means comprising a pivoted carrier lever mounted above the receiving portion of the track means for swinging movement toward and from a carton on the track means, a flexible air suction hose affixed to the free end of said carrier lever, said hose having a free end portion dependent from the carrier lever and terminating in a carton engageable suction cup, a rotated crank-arm to produce timed oscillation of the carrier lever, and a connecting rod connecting said carrier lever with the crank-arm.

ROBERT OTTO WOELFER.
